BALL POINT PEN

Roy M. Jenkins, 3411A W. Alameda, Burbank, Calif.

Filed Aug. 5, 1963, Ser. No. 76,105

Term of patent 14 years

(Cl. D74—17)

FIG. 1 is a side elevational view of a ball point pen, showing my new design;

FIG. 2 is a front elevational view thereof;

FIG. 3 is an enlarged top plan view of FIG. 1;

FIG. 4 is an enlarged bottom plan view thereof;

FIG. 5 is an enlarged sectional view taken on the line 5—5 of FIG. 2; and

FIG. 6 is an enlarged sectional view taken on the line 6—6 of FIG. 2.

The essential features of the design reside in the portions shown in solid lines.

I claim:

The ornamental design for a ball point pen, as shown and described.
